(57) **CLAIM**

The ornamental design for a wireless charger station, as shown and described.

DESCRIPTION

FIG. 1 is a perspective view of a wireless charger station showing embodiment 1 of my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, right, bottom perspective view thereof.

FIG. 9 is a perspective view of a wireless charger station showing embodiment 2 of my new design.

FIG. 10 is a front view thereof.

FIG. 11 is a rear view thereof.

FIG. 12 is a left side view thereof.

FIG. 13 is a right side view thereof.

FIG. 14 is a top view thereof.

FIG. 15 is a bottom view thereof; and,

FIG. 16 is a rear, right, bottom perspective view thereof.

The broken lines in the drawings depict portions of the wireless charger station that form no part of the claimed design.
